(57) CLAIM

The ornamental design for a display screen or portion thereof with graphical user interface, as shown and described.

DESCRIPTION

The sole FIGURE is a front view of a display screen or portion thereof with graphical user interface according to our new design.

The rectangular broken-line perimeter illustrates a display screen or portion thereof and forms no part of the claimed design. The remaining broken lines shown in the drawing show parts of the graphical user interface and form no part of the claimed design.

1 Claim, 1 Drawing Sheet

The image displays a mobile banking application with a light blue header and a white background. At the top, there are several buttons: 'Sign out' (top left), 'Insights & Personalize' (top center), and 'Manage cash controls' (top right). Below these are three main sections, each with a title and a list of account details.

Account Details:

- Checking (3333333333333333)
  - Balance: $11,000.00
  - Type: Cash & Savings
  - Checkings used: $5,400.00
  - Services used: $5,000.00
  - Cards & Loans: $540.00
  - Entry Balance: $224,000.00
  - Entry Deposit: $15,500.00
- Savings (3333333333333333)
  - Balance: $11,000.00
  - Type: Cash & Savings
  - Checkings used: $5,400.00
  - Services used: $5,000.00
  - Cards & Loans: $540.00
  - Entry Balance: $224,000.00
  - Entry Deposit: $15,500.00
- Spending & spending streak
  - Spending streak: 10 days
  - YTD: $11,000.00
  - Fee: $50
  - Max: $500
  - Min: $0
  - Avg: $11,000.00
  - Spending streak: 10 days
  - YTD: $11,000.00
  - Fee: $50
  - Max: $500
  - Min: $0
  - Avg: $11,000.00

Personal Finance:

- Manage cash controls
  - Store Deposit: $100.00
  - Store Deposit: $100.00
  - Due: $100.00
  - Due: $100.00
- Upcoming payments
  - Shel's Gas: $25.00
  - Gas Pending: $0.00
